HOUSEHOLD SCALE

Dana W. Mox, Glenview, Ill., assignor to Hanson Scale
Company, Northbrook, Ill., a corporation of Illinois

Filed Dec. 6, 1963, Ser. No. 77,703

Term of patent 14 years

(Cl. D52—10)

FIG. 1

FIG. 2

FIG. 1 is a front elevational view of a household scale, showing my new design;

FIG. 2 is a side elevational view thereof, the opposite side being a mirror image of the side shown;

FIG. 3 is a rear elevational view thereof; and

FIG. 4 is a top plan view of the scale.

I claim:

The ornamental design for a household scale, as shown and described.
